UNITED STATES PATENT OFFICE.

ORIN C. FENLASON, OF HOQUIAM, WASHINGTON.

VENEER BRANDING OR PRINTING PRESS.

1,078,490.

Specification of Letters Patent. Patented Nov. 11, 1913.

Application filed February 21, 1908. Serial No. 417,167.

To all whom it may concern:

Be it known that I, ORIN C. FENLASON, a citizen of the United States, residing at Hoquiam, in the county of Chehalis and 5 State of Washington, have invented a new and useful Veneer Branding or Printing Press, of which the following is a specification.

The invention relates to a veneer branding 10 or printing press.

Heretofore difficulty has been experienced in applying distinguishing brands or marks to veneer packages by means of printing presses owing to the fact that in the actual 15 process of manufacturing veneer packages, the veneer is cut from a green wet log and immediately, without drying, manufactured into packages, or done up into bundles in the knock-down form, ready for shipment, 20 and to the impossibility of obtaining an ink, which, when applied to green wood taken from western forests, will not be affected by the acid in the wood and caused to run, thereby defacing the impression in such a 25 way as to render it practically impossible to read the same. In the manufacture of common packing boxes, which are usually branded with ink presses, the method of handling the material is different. The lumber is always piled up in a yard to dry, or 30 put through a drying-kiln in order to reduce the weight of the lumber to save the freight, and also to prevent the lumber from warping and checking. Thus, when the material 35 is ready for branding, the ink presses work on it very successfully.

Heretofore there has been comparatively little demand from fruit packers for printing or branding the packages, but there is a 40 growing tendency among packers of fruit to have their stamp put upon each package to establish a reputation for fruit packed by them, and the object of the present invention is to provide a comparatively simple automatic machine, capable of enabling brands or distinguishing marks to be distinctly applied to veneer in a green state.

A further object of the invention is to 45 provide pneumatic mechanism for feeding veneer into the machine, adapted to take the veneer from the top of a pile or stack, whereby the veneer is handled with greater facility and rapidity, and without the injury resulting from the feeding of the veneer 50 from the bottom of a pile or stack by mechanical means.

Another object of the invention is to provide a veneer branding machine having continuously operating carrying mechanism to convey the veneer to and from the branding 60 dies, and provided also with means for arresting the progress of the veneer through the machine during the branding operation without stopping the carrying mechanism, whereby a clear and distinct impression is 65 secured with a rapidly operated machine.

The invention also has for its object to provide means for enabling the veneer to be maintained in engagement with the branding dies the necessary length of time to obtain 70 a clear impression, and for rapidly moving the veneer out of engagement with the branding dies to prevent the veneer from being drawn across the same, and smearing or obliterating the impression, or otherwise 75 impairing the distinctness thereof.

With these and other objects in view, the invention consists in the construction and novel combination of parts hereinafter fully described, illustrated in the accompanying 80 drawings, and pointed out in the claims hereto appended; it being understood that various changes in the form, proportion, size and minor details of construction, within the scope of the invention, may be resorted to without departing from the spirit or 85 sacrificing any of the advantages of the invention.

In the drawings:—Figure 1 is a side elevation of a veneer branding machine, constructed in accordance with this invention. Fig. 2 is a similar view, showing the other side of the machine. Fig. 3 is a plan view of the machine. Fig. 4 is a rear elevation of the machine, the rear veneer-receiving receptacles being removed. Fig. 5 is a central longitudinal sectional view of the same. Fig. 6 is an enlarged vertical sectional view, taken substantially on the line 6—6 of Fig. 90 2, and illustrating the construction of the oscillatory intermittently operated suction mechanism. Fig. 7 is a detail sectional view, taken substantially on the line 7—7 of Fig. 95 6. Fig. 8 is an enlarged transverse sectional view of a portion of the machine, taken 100 substantially on the line 8—8 of Fig. 5, and illustrating the construction of the branding mechanism. Fig. 9 is a detail view of the bed plate and the branding dies. Fig. 10 is an enlarged detail sectional view, taken 110 substantially on the line 10—10 of Fig. 8, and illustrating the construction of the

branding mechanism. Fig. 11 is a detail perspective view of the hollow cross head. Fig. 12 is a detail sectional view on the line 12—12 of Fig. 10. Fig. 13 is a detail sectional view on the line 13—13 of Fig. 10. Fig. 14 is a detail view of one of the perforated covers or plates of the burner casing. Fig. 15 is a detail view of a portion of the bed plate, and illustrating the construction 10 for interlocking the burner casings with the bed plate. Fig. 16 is a detail view of one of the crank wheels. Fig. 17 is a detail view of the adjustable sprocket wheel of the gearing for operating the feeding mechanism. Fig. 18 is a sectional view of the same. Fig. 19 15 is an enlarged detail sectional view, illustrating the manner of slidably mounting the front cross head and the means for connecting the same with the operating gearing and 20 the feeding mechanism.

Like numerals of reference designate corresponding parts in all the figures of the drawings.

The veneer to be branded is placed upon a 25 vertically reciprocatable table 1, arranged at a slight inclination and provided with a plurality of longitudinally disposed magazines or compartments 2, adapted to receive sheets 3 of veneer, arranged in the form of a stack or pile, as clearly illustrated in Fig. 5 of the drawings. The machine is shown equipped with five separate veneer-receiving magazines or compartments, and is adapted to brand simultaneously five long narrow strips 30 of veneer, but it will be readily understood that the table may be constructed to accommodate veneer of any size. The magazines or compartments are formed by longitudinal walls or partitions, and are provided with 35 front walls 4, which terminate short of the upper edges of the side walls or partitions.

The table is mounted upon a cross head 5, provided with an inclined upper face to support the table at an inclination and having 45 vertical end flanges 6, extending longitudinally of the cross head and arranged in vertical guide ways, consisting of slots 7, formed in the sides of the frame of the machine at the front thereof, as clearly illustrated in Figs. 1, 2 and 5 of the drawings. The cross head is also equipped at its ends with horizontal pivots or trunnions 8, and it is connected with crank wheels 9 by adjustable connecting rods 10. The crank 50 wheels, which are mounted on a front transverse shaft 11, are located at opposite sides of the machine, and the adjustable connecting rods are provided with means for varying their length to adjust the table to position the same properly with relation to the feeding mechanism, hereinafter described.

The crank disks or wheels are provided opposite the wrist pins 12 with heavy or weighted portions 13 for counter-balancing 60 the crank wheels. The counter-balancing

weights are formed by increasing the thickness of the heavier half of the wheels, which are equipped with curved guards 14, secured at their terminals to the weighted portions of the crank wheels in recesses thereof and 70 constituting a portion of the periphery of the crank wheels to prevent the shoulders, formed by thickening the said crank wheels, from coming in contact with the operator, or other person. 75

The rotary movement of the crank wheels reciprocates the table and carries the veneer to and from the oscillatory feeding device, comprising a hollow transverse vacuum rock shaft or tube 15, a plurality of upper vacuum or suction tubes 16, and a corresponding number of lower telescopic vacuum or suction tubes 17, provided at their lower ends with veneer-engaging feet 18. The hollow shaft 15, which extends across the front of 80 the machine at the top thereof and which rocks or partially rotates, is journaled in suitable bearings 19 and is connected at its ends with fixed vacuum tubes or pipes 20, extending upwardly from the ends of the 85 hollow shaft and then inwardly toward the median line of the machine to a main air trunk 21. The main air trunk 21, which is located above the median line of the machine, may be arranged at any other convenient point and is connected with a rotary 90 exhaust fan (not shown), which exhausts the air in the main air trunk and creates a suction in the vacuum or suction tubes. The shaft 15, which is provided adjacent to the 95 inner sides of the bearings 19 with shoulders 22, is extended outwardly beyond the bearings into sleeves 23, having inner attaching portions 24, and provided at their outer ends with annular flanges 25. The lower ends 100 of the pipes 20 are provided with annular flanges 26, which are secured to the flanges 25 by means of screws 27, or other suitable fastening devices, suitable packings 28 of rubber, or other material being interposed 105 between the flanges 25 and 26. The screws 27 also pierce metallic collars 29, which are fitted against the outer faces of the flanges 26 to reinforce and clamp the same. By this 110 construction air tight joints between the hollow shaft and the vacuum tubes or pipes 20 are provided. 115

The hollow shaft 15 is provided at the bottom with projecting ribs or bosses 30, and the tubes 16, which depend from the hollow shaft, are provided at their upper ends with flanges 31, secured to the ribs or bosses by screws 32, or other suitable fastening devices. The depending tubes 16 are provided with reduced lower portions 33 to receive the lower telescopic tubes 17, which are provided at their upper ends with annular flanges or enlargements 34, arranged to engage interior shoulders 35, formed by interiorly reducing the lower portions of the 120 125 130

depending tubes. The shoulders 35 serve as stops for limiting the downward movement of the telescopic tubes, and the tubes 16 and 17 form extensible suction devices, and are adapted to accommodate themselves to the reciprocation of the table with varying quantities of veneer in the magazines thereof. Each foot 18 is in the form of a cap having a reduced upwardly extending threaded portion or neck 36 to screw on the lower end of the telescopic tubes, whereby the foot is attached to the same. The bottom of the foot is flat and is provided with a plurality of apertures 37, through which the air is drawn by the exhaust fan. The suction created by the exhaust fan enables each telescopic tube to securely grip and hold a sheet of veneer. When the table is moved upwardly, the veneer is carried into engagement with the telescopic members of the suction devices, and the top sheets of veneer are retained by the same when the table moves downwardly away from the suction devices.

The oscillatory pneumatic feeding device, which engages the sheets of veneer at a point intermediate of the ends thereof, is swung inwardly or rearwardly to feed or deliver the veneer to the carrying mechanism, which conveys the veneer to the branding dies. Motion is communicated from the front of the cross head to the hollow shaft by means of a rod 38 and an arm 39. The rod is connected at its lower end with a horizontal pivot 40 of the cross head by means of a shank or piece 41 into which the lower end of the rod is screwed, a jam nut 42 being provided to prevent the rod from accidentally unscrewing. The arm 39, which extends forwardly or outwardly from the hollow shaft, is secured to the latter by means of a clamp 43, and its outer end 44 is bifurcated and is provided with opposite bearings to receive a pin or pivot 45, through which the rod 38 passes. The upper portion 46 of the rod is threaded to receive a pair of nuts 47, which adjustably position a cushion 48 on the rod. A metallic washer 49 is interposed between the nuts and the cushion to form a backing for the latter. The rod 38, which is adapted to slide through the perforation 50 of the pin or pivot 45, carries a coiled spring 51, interposed between the nut 42 and the pin or pivot 45 and arranged to be compressed when the rod moves upward independently of the arm, after the latter has reached the limit of its upward movement. The arm is swung downwardly by the rod 38 to feed the veneer inwardly, and the said rod forms a substantially rigid connection between the feeding device and the gearing during such movement of the former, the buffer or cushion 48 being in engagement with the pin during such movement of the feeding device.

65 The return or forward movement of the

feeding device is effected through the spring 51, and a plurality of horizontally disposed coiled springs 52, arranged in advance of the tubes 16, and secured at their rear ends to the same, and connected at their front ends to a transverse portion 53 of a substantially U-shaped frame 54. The tubes 16 are provided at their front sides with eyes, to which the rear ends of the coiled springs 52 are connected, and the U-shaped frame, which is composed of two short sides and the transverse connecting portion 53, is provided at the latter with depending lugs 55, to which the outer or front ends of the springs 52 are secured. These springs 52 are distended, when the feeding device is swung inwardly or rearwardly, and they assist in returning the oscillatory feeding device to its initial position, and for maintaining the same in such position, while the veneer is being carried upward to the telescopic members. The forward or return movement of the oscillatory feeding device is limited by means of a transversely disposed buffer 56, extending across the front of the machine and consisting of a strip of rubber, or other suitable material, mounted in the groove of a channel bar 57. The channel bar 57, which is composed of upper and lower sides or flanges, and a connecting portion, is provided at the said sides or flanges with segmental recesses 58, arranged at intervals and located opposite the tubes 16, and adapted to expose portions of rubber, and to arrange the metallic portions beyond the feeding device to prevent the channel bar from being struck by the tubes 16.

The crank wheels rotate in the direction of the arrow in Fig. 2 of the drawings, and when the wrist pin moves upwardly at the inner or rear side of the crank wheels, the table is moved upwardly and the oscillatory feeding device is moved forwardly, or in the direction of the front of the machine. The oscillatory feeding device is at the limit of its forward movement, and in engagement with the buffer 56, when the table is at the center of its stroke, and the wrist pin is midway between the top and bottom of the crank wheels. Further upward movement of the wrist pin carries the cushion 48 away from the pin or pivot 45, which is engaged and held against downward movement by the spring 51. The coiled spring 51 gradually increases in tension with the upward movement of the table, and the feeding device is held tightly at the limit of its forward movement and is caused to engage the veneer at the same point during each operation of the machine, so that the veneer will be uniformly fed to the carrying means, hereinafter described. The spring constitutes a yieldable connection between the feeding mechanism and the operating mechanism, while the table is moving upward in-

70

130

dependently of the said feeding mechanism. The first half of the downward throw or movement of the connecting rod 10 returns the cushion 48 to the position shown in Fig. 2 of the drawings, and the second half swings the feeding mechanism rearwardly from the forward position illustrated in full lines in Figs. 2 and 5 of the drawings to the dotted position shown in Fig. 5. The first half of the upper throw or movement of the connecting rod swings the feeding mechanism forwardly. The branding, as hereinafter fully explained, occurs during the second half of the upward stroke or movement of the connecting rod, and the first half of the downward throw or movement, while the feeding mechanism is at the limit of its forward movement.

Motion is communicated to the shaft 11 by sprocket gearing, consisting of a longitudinally disposed sprocket chain 60, and front and rear sprocket wheels 61 and 62. The front sprocket wheel 61, which is arranged on the shaft 11, is adjustably secured to a disk 63, provided with an annular series of perforations 64 and keyed, or otherwise secured to the shaft 11. The perforations 64 are adapted to receive screws 65, which engage threaded perforations 66 of the sprocket wheel 61. The adjustment of the sprocket wheel 61 enables the feeding mechanism to be operated to feed the veneer at the proper time. Any other suitable means, however, may be employed for adjustably mounting the front sprocket gear on the shaft 11, and if desired, other gearing may be employed for communicating motion to the crank wheels.

The veneer is conveyed to and from the branding mechanism, hereinafter described, by means of lower front and rear continuously rotating wheels 67 and 68, arranged in transverse series and mounted on transverse shafts 69 and 70, and coöperating with upper front and rear idlers or gravity wheels 71 and 72. The shafts 69 and 70 are journaled in suitable bearings of the sides of the frame, and they are equipped with spur wheels 73 and 74, which mesh with a large spur gear wheel 75, mounted on a shaft 76 and also meshing with a gear 77 of a counter shaft 78. The shaft 78 is also provided with a pulley 79, which receives a driving belt 80, extending downward through the floor 55 to a suitable driving pulley. The machine will generally be arranged on one of the upper floors of a factory, but it may be operated at any other place, and the driving belt will be arranged to correspond to the position of the machine with relation to the driving shaft. The rear sprocket wheel 62 is mounted on the shaft 76, and the gear 75 rotates in the direction of the arrow in Fig. 1 of the drawings. This rotates the wheels 67 and 68 in the proper direction for car-

rying the veneer to and from the branding mechanism. The upper flight or stretch of the sprocket chain 60 also travels forwardly or in the direction of the front of the machine, and this secures the operation of the crank wheels heretofore explained.

The front and rear veneer-carrying wheels 67 and 68, which are arranged in spaced relation, as clearly illustrated in Figs. 3 and 4 of the drawings, extend in advance and in rear of a transversely disposed bed plate 81, and the upper gravity wheels, which yieldably hold the veneer in engagement with the lower positively driven wheels, are journaled between oscillatory arms 82 and 83, arranged in pairs and connected by sleeves, mounted on front and rear transverse rods 84 and 85. The gravity wheels 71 and 72 exert a sufficient pressure on the veneer to secure a positive and rapid movement of the same through the machine, when the veneer is free to move, and they enable the movement of the veneer through the machine to be arrested during the branding operation, as hereinafter explained, without stopping the rotary movement of the carrier wheels 67 and 68. The tensile strength of the veneer is sufficient to enable this result to be accomplished without injury to the material.

The bed plate 81, which extends across the machine, is supported by flanges 86, extending inwardly from the sides of the frame of the machine, as clearly illustrated in Fig. 8 of the drawings, and the terminals of the bed plate are secured upon the said flanges by means of screws 87, which pierce the sides of the frame and engage threaded sockets or perforations of the bed plate. The bed plate is provided in its upper face with a depression or recess 88, across which the veneer moves, and into which the veneer is depressed during the branding operation. The front and rear edges of the transversely disposed bed plate are oppositely beveled, and the plate is provided at intervals with circular openings 89, arranged in alignment with the magazines or compartments of the table and in the path of the veneer. The bed plate is provided at each opening 89 with an annular recess 90, forming a seat for an annular flange 91 of a burner casing 92. The burner casing, which depends from the bed plate, is in the form of a pot or receptacle, and is provided in its bottom with a central threaded opening 93, into which a gas supply pipe 94 is screwed, or otherwise secured. The bed plate is also provided at each opening with a lug or projection 95, formed by a pin and adapted to fit in a corresponding recess 96 of the annular flange 91 of the burner casing, whereby the burner casing is interlocked with the bed plate and held against rotary movement in the opening 89. The 130

burner casing is provided at the upper face of the annular flange with an annular recess 97, forming a seat for a perforated plate or cover 98 upon which the branding die 99 is mounted. The plate 98 is in the form of a disk and is provided at its periphery with a recess 100, adapted to be engaged by a projection or stud 101, consisting of a pin mounted on the burner casing at the recess 10 or seat thereof, whereby the die supporting plate is interlocked with the burner casing, and is held against rotary movement. By interlocking the burner casing with the bed plate and the die supporting plate with the burner casing, the branding die is held against accidental rotary movement, and cannot become displaced during the operation of the machine. This will properly place the impression on the sheet with relation to the edges of the veneer passing through the machine. The branding dies may be equipped with any distinguishing marks or devices, or other matter to be printed or branded on the veneer, and they are detachable and interchangeable, and may be readily placed in and removed from the machine, so that the latter may be equipped with proper branding dies.

Each burner casing is equipped with a gas burner 102, or other suitable heating device for maintaining the dies at the proper temperature to secure a perfect brand or impression. The burner 102 is connected with the supply pipe 94, extending downwardly to a transversely disposed gas pipe 103, which is connected with each of the supply pipes 94. The individual pipes 94 extending to the burner casings, are provided with cocks or valves 104, so that the flow of gas to any of the burners may be stopped or controlled. The transverse pipe 103 is designed to be connected with an ordinary gas supply pipe, but when the machine is operated at places not equipped with gas works, the supply pipe 103 may be utilized for gasoline, or other liquid hydrocarbon fuel, and the machine is equipped with an air pump or compressor 105 for affording a sufficient supply of compressed air for such purpose. The air pump 105, which is mounted on the frame of the machine at one side thereof, is provided with a piston 106, which is connected with the front cross head 5 by means of a stud or projection 107, extending from one end of the cross head similar to the pivot or projection 40.

The veneer is delivered to the front wheels of the carrying mechanism by the oscillatory feeding device, which introduces the inner end of the veneer between the upper and lower wheels 71 and 67. The veneer is gripped by the front carrying wheels with sufficient force to disengage it from the suction devices, and it is rapidly carried rearwardly through the machine until its move-

ment is arrested. The veneer is moved across the top of the bed plate, and during its passage across the recess or depression 88, the sheets of veneer are first gripped by a series of clamping plungers 108, located at 70 the rear portion of the bed plate and adapted to arrest the movement of the veneer without stopping the carrying mechanism. The veneer is then depressed into the recess by a series of branding plungers 109, which bow or buckle the sheets of veneer and carry the same into contact with the branding dies and hold the veneer against the same a sufficient length of time to secure a perfect impression or brand. The branding plungers 109 are then moved upwardly out of engagement with the veneer, which, through its resiliency, straightens out and thereby springs out of contact with the branding dies, and effectually prevents the impressions from being streaked or smeared through any movement of the veneer while in contact with the branding dies. This arresting of the movement of the veneer without stopping the mechanism for carrying or feeding the veneer to the branding mechanism enables a perfect impression to be obtained with a machine operated at a high rate of speed, and a machine of maximum branding capacity is produced, while the cost of branding veneer is reduced to a minimum.

The branding plungers are carried by a vertically reciprocatable hollow cross head 110, extending across the machine at a point above the bed plate, and provided with terminal projections 111, arranged in a vertical series at each end of the cross head 110, and slideable in guide-ways 112, consisting of slots formed in the sides of the frame of the machine. The projections are arranged at the upper and lower edges of the cross head 110, and at points intermediate of the same, and the intermediate projections are provided with horizontal pivots 113, which are connected by adjustable connecting rods 114 with eccentrics 115 of the transverse shaft 76. The straps of the eccentrics 115 are rigid with and form a part of the lower ends of the connecting rods 114, which are adapted to be lengthened and shortened to adjust the hollow cross head toward or from the bed plate. By adjusting the cross head upwardly and downwardly through the extensible connecting rods, the branding plungers may be caused to engage the stock sooner or later, and thereby enable the brand to be placed at the desired point. This adjustment also regulates the time the veneer remains in contact with the branding dies. The rotation of the shaft 76 imparts a vertically reciprocatable motion to the cross head, which is arranged horizontally.

The branding plungers consist of squared lower portions 116 and round upper portions 117; the cross head 110 is provided with 130

aligned upper and lower rectangular openings 118 and 119, and the branding plungers 109 are guided in the bottom openings 119 and in openings 120 of a top plate 121. The 5 upper rectangular openings are of a size to permit the lower portions of the branding plungers to be passed through them, while the openings 120 of the top plate 121 are of a size to fit the round upper portions 10 or stems of the branding plungers. The branding plungers are also provided at an intermediate point with integral collars or enlargements 122, arranged to engage the bottom of the cross head 110, when the latter 15 is moved upward to carry the branding plungers out of contact with the veneer. The hollow rear cross head 110 is also equipped with a bottom plate 123, provided with rectangular openings, which register 20 with the bottom openings of the cross head and coöperate with the same in guiding the lower portions of the guiding plungers. The upper and lower plates 121 and 123, which are secured to the top and bottom of the 25 cross head 110 by screws, or other suitable fastening devices, project rearwardly from the cross head and are provided with upper and lower guide openings 124 and 125 for the clamping plungers 108. The round 30 upper portions of the branding plungers receive coiled springs 126, located within the cross head and interposed between the top plate 121 and the shoulders, formed by the collars or enlargements 122 and arranged 35 to yieldably maintain the branding plungers in engagement with the veneer. The tension of the spring increases with the downward movement of the cross head, after the plungers have engaged the veneer and 40 carried the same into contact with the branding dies.

The clamping plungers are provided at their lower portions with integral collars or enlargements 127, adapted to rest upon 45 the bottom plate 123 to limit the downward movement of the clamping plungers, and also form shoulders, which are engaged by coiled springs 128, disposed on the upper portions of the clamping plungers and interposed 50 between the collars 127 and the top plate. The lower ends of the clamping plungers extend below the branding plungers, when the said plungers are out of contact with the veneer, and the clamping plungers are 55 thereby enabled to engage and hold the veneer before the same is carried into contact with the branding dies by the plungers 109. The clamping plungers are located above the rear portion of the bed plate 60 and engage the veneer in rear of the branding dies, and they do not release the veneer until the branding plungers, by their upward movement, have permitted the veneer, through its resiliency, to spring out 65 of contact with the branding dies.

The branding plungers 109 are provided at their lower ends with heads 129, which are equipped with front upwardly inclined guides 130 for directing the veneer into the spaces between the branding plungers and the bed plate, should the veneer in its rearward movement come in contact with the guides. The head 129 consists of upper and lower plates secured together by rivets, or other suitable fastening devices, as clearly 70 illustrated in Fig. 10 of the drawings. The upper plate is provided with a rectangular opening 131 to receive the lower end of the branding plungers, which are provided with a reduced portion 132, piercing the lower 80 plate of the head and headed or riveted at the lower face of the same, whereby the plunger heads are secured to the plungers 109. The rectangular opening 131 of the upper plate of the head 129 interlocks the 85 latter with the plunger 109 and prevents the head from rotating on the central integral fastening device 132. The guide, which projects forwardly from the head 129 of each of the plungers, consists of a plate 90 secured to the head 129 and forming the lower face thereof.

The weight of the hollow cross head and the plungers is counter-balanced by coiled springs 133, located within the hollow cross 95 head at the ends thereof, and disposed on vertical bars or members 134, consisting of rectangular lower portions and round upper portions similar to the branding plungers. The lower squared portions of the bars or 100 members 134 extend through lower rectangular openings of the bottom of the hollow cross head, and rest upon the bed plate at the ends thereof, and are supported by the same. The upper round portions of the 105 bars or members 134 extend through round perforations of the top plate 121, and the springs 123 are interposed between the said top plate 121 and shoulders, formed by the upper ends of the squared portions of the 110 bars or members 134. The coiled springs are of sufficient strength to counter-balance the hollow cross head, and enable the same to be readily moved upwardly and downwardly.

When the veneer is held stationary by the clamping plungers, the upper gravity wheels come in contact with the veneer and also remain stationary while the lower continuously operated carrying wheels rotate and move over the lower surface of the veneer without actuating the same. As soon as the veneer is released by the clamping plungers, the carrying wheels rapidly complete the movement of the veneer through the machine and discharge the veneer upon a rear table 135, provided with a plurality of compartments 136 corresponding to the compartments of the front table and open at the front and rear ends. The table is supported 120 125 130

at its inner or front end by a bracket 137, secured to the frame of the machine at the back thereof and to the front end of the rear table 135. The rear end of the table is arranged on a suitable support 138, consisting of spaced sides or legs, and a top connecting bar 139, extending across the lower face of the top of the table.

The branded veneer projects beyond the rear end of the table to facilitate its removal from the compartments thereof, and the rearward movement of the veneer is limited by a plurality of adjustable stops 140, consisting of vertical rods depending from a transverse rod 141, which is supported by a pair of longitudinally adjustable bars 142. The bars 142, which are provided at their front portions with longitudinal slots 143, are mounted upon transverse bars or members 144 and 145, extending across the tops of the veneer compartments 136 and supported by the walls thereof. The depending rods 140 are moved toward and from the rear ends of the compartments 136 through the adjustment of the bars 142, to arrange them to suit the length of the strips of veneer operated on by the branding machine. The rearwardly projecting portions of the branded veneer are exposed between the rear end of the table and the depending rods or stops 140, and are adapted to be conveniently grasped by the operator for removing the branded veneer from the machine.

Having thus fully described my invention, what I claim as new and desire to secure by Letters Patent, is:—

1. A veneer branding machine including continuously operating veneer carrying mechanism, a table arranged to receive the veneer, an oscillatory feeding device arranged to swing from the table to the carrying mechanism to feed the veneer to the latter, means for branding a distinguishing mark or impression on the veneer, separate means independent of the branding means for clamping the veneer at the face thereof to arrest the movement of the veneer through the machine and to hold the said veneer while the impression or distinguishing mark is being applied to the same.

2. A machine of the class described including continuously operating veneer carrying mechanism, means for holding a stack of sheets of veneer, a feeding device movable backwardly and forwardly between the stack and the veneer carrying mechanism to feed the sheets to the latter, means for branding an impression or distinguishing mark on the veneer while the same is in the carrying mechanism, separate means independent of the branding means for clamping the veneer at the face thereof to arrest the movement of the veneer to hold the latter while the distinguishing mark or impression

is being applied without stopping the carrying mechanism.

3. A machine of the class described comprising means for holding a stack of sheets of veneer, veneer carrying mechanism including a lower continuously rotating member, and an upper idler member for holding the veneer in contact with the continuously rotating member, a feeding device movable backwardly and forwardly between the stack and the carrying mechanism for feeding the veneer between the said members thereof, means for applying a distinguishing mark or impression on the veneer, and separate means for clamping the veneer at the face thereof to arrest the progress of the veneer to hold the same without stopping the carrying mechanism while the impression or mark is being applied to the veneer.

4. A machine of the class described comprising means for holding a stack of sheets of veneer, carrying mechanism including lower front and rear continuously operating wheels, and front and rear upper gravity acting wheels for maintaining the veneer in contact with the continuously rotating wheels, a feeding device movable back and forth between the stack and the carrying mechanism for feeding the veneer to the front wheels thereof, means located between the front and rear wheels and movable toward and from the veneer for applying a distinguishing mark or impression to the same, and yieldable means carried by the mark or impression applying means and arranged to operate in advance of the same to clamp the veneer while the mark or impression is being applied.

5. A machine of the class described comprising means for holding a stack of sheets of veneer, continuously operating carrying mechanism including upper and lower front and rear wheels, a feeding device movable back and forth between the stack and the carrying mechanism for feeding the sheets of veneer between the front wheels, means located between the front and rear wheels of the carrying mechanism for applying a distinguishing mark or impression to the sheets of veneer, and separate means for same, a yielding means carried by the mark clamping the veneer at the face thereof to hold the same stationary without stopping the carrying mechanism while the mark or impression is being applied to the veneer.

6. A machine of the class described comprising means for holding a stack of sheets of veneer, continuously operating carrying mechanism, a feeding device movable back and forth between the stack and the carrying mechanism for feeding the sheets of veneer to the latter, a relatively fixed branding die located out of the path of the veneer, a support for the branding die, means for heating the branding die, means for

pressing the veneer against the branding die, and separate means independent of the branding die for engaging the face of the veneer to clamp the same against a support 5 to hold the veneer stationary during the branding operation.

7. In a machine of the class described, the combination with veneer-carrying mechanism, and means for branding the veneer 10 including a branding die, and means for heating the same, of means for pressing the veneer against the die, means independent of the branding means for holding the veneer stationary during the branding operation, and means for causing the veneer 15 to spring out of contact with the die prior to releasing the said veneer.

8. A veneer branding machine comprising continuously operating carrying mechanism, branding mechanism including a relatively fixed branding die located out of the path of the veneer, a support for the branding die, and means for heating the branding die, a plunger for pressing the veneer 25 against the die, and separate means for clamping the veneer at the face thereof against the support to hold the veneer stationary without stopping the carrying mechanism during the branding operation.

30 9. A veneer branding machine comprising continuously operating veneer carrying mechanism, branding mechanism having a supporting surface and including a relatively fixed branding die located out of the 35 path of the veneer, and means for heating the branding die, a plunger for pressing the veneer against the branding die, and a clamping device arranged to engage the face of the veneer to clamp the same against the 40 supporting surface for holding the veneer stationary during the branding operation.

10. In a machine of the class described, the combination with veneer-carrying mechanism, of branding mechanism including a branding die, and means for heating the same, and a plunger for pressing the veneer against the die, and a clamping plunger arranged to engage the veneer prior 45 to the said plunger for holding the veneer 50 stationary during the branding operation, said branding mechanism being also provided with means for disengaging the veneer from the die prior to releasing the said veneer.

55 11. In a machine of the class described, the combination with a bed plate having a depression or recess, a branding die located within the recess below the top of the bed plate, means for heating the branding die, 60 means for moving the veneer over the depression, and means for forcing the veneer into the depression to carry the former into contact with the branding die, said veneer being thereby buckled or bowed, whereby it

is caused to spring out of engagement with 65 the die.

12. In a machine of the class described, the combination with a bed plate having a depression or recess, of a branding die located in the depression or recess, means for 70 moving the veneer over the depression or recess, means for forcing the veneer into the depression or recess to carry the same into contact with the branding die, and means for clamping the veneer on the bed plate to 75 hold the former stationary during the branding operation, said veneer being buckled or bowed when forced into the depression or recess, whereby it is caused to spring 80 out of engagement with the branding die. 80

13. In a machine of the class described, the combination of a plate having a depression or recess, a branding die arranged within the depression or recess, means for moving the veneer over the bed plate, a branding 85 plunger for forcing the veneer into the depression or recess to carry the said veneer into contact with the branding die, and a clamping plunger for engaging the veneer to hold the same stationary during the 90 branding operation.

14. In a machine of the class described, the combination of a bed plate having a branding die, veneer-carrying means including lower continuously rotating wheels extending in advance and in rear of the bed plate, and upper idlers for holding the veneer in contact with the lower wheels, a branding plunger for pressing the veneer against the die, and a clamping plunger 100 co-operating with the bed plate for clamping the veneer against the bed plate to hold the said veneer stationary during the branding operation. 100

15. A veneer branding machine comprising veneer carrying mechanism, a branding die located beneath the veneer and having heating means, a vertically reciprocatable plunger located above the veneer and arranged to carry the same into engagement 110 with the branding die, and separate means independent of the plunger for engaging the face of the veneer to clamp the same against a supporting surface to hold the veneer stationary during the branding operation. 115

16. A veneer branding machine comprising veneer carrying mechanism, a branding die located beneath the veneer and having heating means, a vertically reciprocating 120 cross head located above the veneer, a yieldably mounted branding plunger carried by the cross head and arranged to press the same against the branding die, and separate means independent of the plunger and carried by the cross head for engaging the veneer at the face thereof to hold the veneer 125 stationary during the branding operation.

17. In a machine of the class described, the combination with veneer-carrying mechanism, of a branding die located beneath the veneer and having heating means, a vertically reciprocating cross head located above the veneer, a yieldably mounted branding plunger carried by the cross head and arranged to engage the veneer to press the same against the branding die, and a yieldably mounted clamping plunger carried by the cross head for engaging and holding the veneer stationary during the branding operation.

18. In a machine of the class described, the combination with veneer carrying mechanism, of a branding die located beneath the path of the veneer, and a vertically movable plunger arranged above the path of the veneer and provided at its lower engaging end with an inclined guide.

19. In a machine of the class described, the combination with veneer-carrying mechanism, of a branding die located beneath the path of the veneer and having heating means, a reciprocatable plunger located above the path of the veneer and provided at its lower end with an engaging head secured to and interlocked with the plunger, and a guide fixed to the head and having an inclined guiding portion located in advance of the plunger and extending upwardly from the head.

20. A veneer branding machine comprising a bed plate having an opening, a casing mounted in and depending from the opening, heating means located within the casing, a branding die located above the heating means and below the top of the bed plate, and means for flexing the veneer to carry the same into contact with the branding die.

21. A veneer branding machine comprising a bed plate having an opening, a casing depending from the opening, heating means located within the casing, a perforated cover for the casing, a branding die supported by the cover below the top of the bed plate, and means for flexing the veneer to carry the same into contact with the branding die.

22. A veneer branding machine comprising a bed plate having a circular opening, a casing mounted in the opening, heating means located within the casing, a branding die arranged above the heating means and below the top of the bed plate, means for locking the branding die against rotary movement, and means for flexing the veneer to carry the same into contact with the branding die.

23. In a machine of the class described, the combination of a bed plate having a circular opening and provided with a projection, a casing mounted in the opening

and provided with a recess to receive the projection, said casing being also provided with a projection, a perforated plate or cover fitted in the casing and having a recess to receive the projection thereof, a branding die supported by the perforated plate or cover below the top of the bed plate, and means for carrying the veneer into contact with the branding die.

24. In a machine of the class described, the combination with veneer-carrying means, of a branding die located beneath the path of the veneer, a vertically reciprocatable cross head, a branding plunger carried by the cross head for forcing the veneer into contact with the branding die, a spring for counter-balancing the weight of the cross head and the plunger, and means for supporting the spring.

25. In a machine of the class described, the combination with a plurality of relatively fixed branding dies, of a vertically movable cross head, a plurality of vertical plungers carried by the cross head, a rod piercing the cross head, a spring disposed on the rod and engaging the cross head to counter-balance the same, and mechanism for reciprocating the cross head.

26. A veneer branding machine comprising a bed plate provided with a plurality of relatively fixed branding dies, mechanism for simultaneously carrying a plurality of sheets of veneer across the top of the bed plate, a reciprocatable cross head located above the bed plate, a plurality of plungers slideable in the cross head and arranged to force the veneer into contact with the branding dies, springs engaging the plungers and the cross head for holding the plungers yieldably in engagement with the veneer, and means for engaging the upper face of the veneer to clamp the same against a supporting surface.

27. In a machine of the class described, the combination with veneer-carrying mechanism, of a bed plate provided with a plurality of branding dies, a reciprocatable cross head located above the bed plate, a plurality of plungers slideable on the cross head and arranged to force the veneer into contact with the branding dies, and springs engaging the plungers and the cross head for holding the plungers yieldably in engagement with the veneer, said plungers being also provided with means for engaging the cross head for limiting their relative downward movement.

28. In a machine of the class described, the combination of a bed plate provided with a plurality of branding dies, a hollow reciprocatable cross head located above the bed plate, a plurality of branding plungers piercing the cross head, springs housed within the cross head and engaging the

plungers, rods supported upon the bed plate and piercing the cross head, and springs mounted on the rods and also housed within the cross head and engaging the same for counter-balancing the cross head and the plungers.

29. In a machine of the class described, the combination of a bed plate provided with a plurality of branding dies, a reciprocatable cross head located above the bed plate, a plurality of branding plungers carried by the cross head for forcing the veneer against the dies, a plurality of clamping plungers slidably mounted on the cross head 10 and arranged to clamp the veneer against the bed plate, and springs for yieldably holding the clamping plungers in engagement with the veneer.

30. In a machine of the class described, 20 the combination of a bed plate provided with a plurality of branding dies, a reciprocatable cross head located above the bed plate, a plurality of branding plungers carried by the cross head, springs for engaging 25 the plungers and forming yieldable connections between the same and the cross head when the plungers are in engagement with the veneer, rods piercing the cross head, springs mounted on the rods for counter-balancing the cross head, a plurality of 30 clamping plungers carried by and slidably connected with the cross head and arranged to hold the veneer against the bed plate, and springs mounted on the clamping plungers and forming yieldable connections 35 between the same and the cross head when the said clamping plungers are in engagement with the veneer.

31. In a machine of the class described, 40 the combination of a bed plate, a plurality of burner casings, burners arranged within the casings, branding dies arranged above the burners below the top of the bed plate, a supply pipe provided with a plurality of 45 branches extending to the said burners, means for carrying the veneer over the bed plate, and means for flexing the veneer to force the same into contact with the branding dies.

50 32. In a machine of the class described, the combination with veneer-carrying mechanism, of a die located beneath the path of the veneer, a reciprocatable cross head having means for engaging and flexing the veneer for carrying the same into contact with the die, and means for reciprocating the cross head adjustably connected with the same.

60 33. A veneer branding machine including a bed plate, a die located below the top of the bed plate, mechanism for carrying veneer across the top of the bed plate, a reciprocatable cross head having means for flexing the veneer to depress the same into

contact with the die, an eccentric, and adjustable means connected with the eccentric and with the cross head.

34. A veneer branding machine comprising a frame, a bed plate provided with a plurality of dies, each arranged below the 70 top of the bed plate, mechanism for carrying the veneer across the top of the bed plate, a cross head guided in the frame and provided with means for flexing the veneer to depress the same into contact with the dies, 75 means for reciprocating the cross head, and means for adjusting the cross head with relation to the dies.

35. In a machine of the class described, 80 the combination with a frame, of a die, mechanism for carrying veneer across the die, a reciprocatable cross head having means for engaging the veneer to press the same against the die, a vertically movable table, an oscillatory device for feeding the 85 veneer from the table to the carrying mechanism, means for adjusting the cross head for controlling the engagement of the veneer by the former, and adjustable means for communicating motion to the table and the 90 oscillatory device for feeding the veneer at the proper time.

36. A veneer branding machine including means for holding a stack of sheets of veneer, continuously operating veneer carrying mechanism, a feeding device movable back and forth between the stack and the veneer carrying mechanism for feeding the sheets of veneer to the latter, branding mechanism having heating means and provided with a supporting surface, and means for clamping the veneer at the upper face thereof against the supporting surface to stop the veneer during the branding operation without stopping the carrying mechanism.

37. A veneer branding machine including means for holding a stack of sheets of veneer, continuously operating veneer carrying mechanism, an intermittently operating feeding device movable back and forth between the stack and the carrying mechanism to feed the sheets of veneer to the latter, means for branding the veneer while the same is in the carrying mechanism, said branding means having a supporting surface and separate means for clamping the veneer at the upper face thereof to hold the same against the supporting surface to stop the veneer during the branding operation without stopping the carrying mechanism.

38. In a machine of the class described, the combination of intermittently operated veneer feeding mechanism, continuously operated veneer-carrying mechanism arranged to receive the veneer from the feeding mechanism, means for branding the veneer, means for heating the branding means, and

means for stopping the veneer during the branding operation without stopping the carrying mechanism.

39. In a machine of the class described, 5 the combination with veneer carrying mechanism, and means for applying a distinguishing mark or impression to the same, of a table provided with a plurality of veneer receiving compartments, a plurality of 10 stops spaced from the compartments and located beyond the ends of the table in position for permitting the veneer to project beyond the outer end of the table, a transverse rod supporting the stops, and means for adjustably connecting the rod with the table.

40. In a machine of the class described, the combination with veneer-carrying mechanism, and means for applying a distinguishing mark or impression to the same, of 20 a table provided with a plurality of veneer-receiving compartments, a plurality of stops spaced from the compartments and located beyond the end of the table to cause the veneer to project from the end of the latter, 25 a transverse rod supporting the stops, and means for adjustably connecting the rod with the table.

41. In a machine of the class described, the combination with veneer-carrying mechanism, and means for applying a distinguishing mark or impression to the same, of 30 a table provided with a plurality of veneer-receiving compartments, a plurality of stops spaced from the compartments and located 35 beyond the end of the table to cause the veneer to project from the end of the latter, a transverse rod supporting the stops, and longitudinal bars or members adjustably connecting the rod with the table.

40 42. In a machine of the class described, the combination of a bed plate, carrying wheels arranged below and in advance and in rear of the bed plate, means for feeding sheets of veneer to the carrying wheels, 45 a branding die arranged in the bed plate below the top thereof, and means for forcing the veneer against the die.

43. In a machine of the class described, the combination of a relatively fixed bed 50 plate, a branding die seated within the same below the top surface thereof, means for heating the branding die, the top surface of the bed plate in front and in rear of the die being beveled, and means for feeding 55 veneer across the top of the bed plate.

44. In a machine of the class described, the combination of a bed plate, a branding die seated within the same, a branding plunger for pressing the veneer against the die, 60 and a separate clamping plunger arranged to engage the upper face of the veneer to clamp the same against the bed plate for holding the veneer at one side of the die.

45. In a machine of the class described,

the combination of a bed plate, a branding 65 die seated within the same, a branding plunger for pressing the veneer against the die, and a separate clamping plunger for holding the veneer at one side of the die, the lower end of the clamping plunger being 70 extended below the lower end of the branding plunger when the parts are in their initial position.

46. In a machine of the class described, 75 the combination of a bed plate, a branding die seated in the same below the top surface thereof and having heating means, means for feeding veneer to the bed plate to cause it to extend over and be supported out of contact with the branding die, and 80 means for flexing the veneer opposite the die into contact therewith, whereby upon reverse movement of the flexing means the veneer through its resiliency springs upwardly from the die. 85

47. A machine of the class described including continuously operating veneer carrying mechanism, means for holding a stack of veneer, a feeding device arranged to move back and forth between the stack and 90 the veneer carrying mechanism to feed the veneer to the latter, means movable toward and from the veneer for applying a distinguishing mark or impression to the same while the latter is in the carrying mechanism, and means carried by the mark or impression applying means and arranged to engage the veneer in advance of the same for holding the veneer stationary while the mark or impression is being applied. 100

48. A machine of the class described including continuously operating veneer carrying mechanism, means for holding a stack of veneer, a feeding device arranged to move back and forth between the stack and 105 the veneer carrying mechanism to feed the veneer to the latter, means for applying a distinguishing mark or impression on the veneer while the latter is in the carrying mechanism, and separate means for clamping the veneer at the face thereof to arrest the movement of the veneer through the machine and to hold the said veneer while the impression or distinguishing mark is 110 applied to the same. 115

49. A machine of the class described including continuously operating veneer carrying mechanism, means for supporting a stack of sheets of veneer, a feeding device, means for moving the feeding device back 120 and forth between the stack and the veneer carrying mechanism to feed the veneer to the latter, means for branding a distinguishing mark on the veneer while the latter is in the carrying mechanism, means for causing 125 the veneer to move out of contact with the branding means, and means for clamping the veneer to arrest the movement of the

same through the machine until after the veneer has been branded and has moved out of contact with the branding means.

50. A machine of the class described including means for holding a stack of sheets of veneer, front and rear carrier wheels continuously operated for carrying the veneer through the machine, a feeding device, means for moving the feeding device back and forth between the stack and the front carrier wheels for feeding the veneer to the latter, and means located between the front and rear carrier wheels for applying a distinguishing mark or impression to the veneer.

51. A machine of the class described including means for holding a stack of sheets of veneer, front and rear carrier wheels continuously operated for carrying the veneer.

neer through the machine, a feeding device, 20 means for moving the feeding device back and forth between the stack and the front carrier wheels for feeding the veneer to the latter, means located between the front and rear carrier wheels for applying a distinguishing mark or impression to the veneer, 25 and means for clamping the veneer at the upper face thereof to hold the same against a supporting surface while the mark or impression is being applied to the veneer. 30

In testimony, that I claim the foregoing as my own, I have hereto affixed my signature in the presence of two witnesses.
